UNITED STATES PATENT OFFICE.

ERNST RUBEN DAHLSTROM, OF STOCKHOLM, SWEDEN, ASSIGNOR TO AKTIEBOLAGET FORMATOR, OF STOCKHOLM, SWEDEN, A CORPORATION.

MACHINE FOR SHAPING A TOBACCO MASS.

Application filed September 3, 1926, Serial No. 133,490, and in Sweden December 9, 1925.

This invention relates to machines, for shaping a tobacco mass, in which a quantity of tobacco is compressed in a receiver. The receiver consisting generally of a compression 5 chamber and a movable piston is provided with an inlet opening in one of its walls below the retracted position of the piston through which the tobacco enters the chamber of the receiver and is compressed by the inward movement of the piston.

Machines of this kind as hitherto known act satisfactorily when the treated tobacco is short cut, but if they are used with long cut tobacco it results that some of the tobacco quantity sought to be compressed in the receiver chamber does not enter into the receiver but remains in or outside the opening after the compressing member, which moves along the wall in which the inlet opening is arranged, 20 has passed the said opening during its working stroke.

The object of the present invention is to overcome such faulty operation, by providing positive means for moving the tobacco 25 through the inlet opening into the chamber of the receptacle before the piston is moved to compress the tobacco.

A further object of the invention is to provide one of the walls of the receptacle with a pivoted part which will close the inlet opening and when moved to closed position will force all the tobacco into the compression 30 chamber.

In the annexed drawing are shown different 35 embodiments of the invention and in which:

Fig. 1 shows a front view of a machine of the above mentioned type in which the present invention is used. Fig. 2 shows a section along the line A—A in Fig. 2, and Fig. 3 is a 40 section along the line B—B in Fig. 2. Figs. 4, 5 and 6 shows the device in three different working positions. Fig. 7 is a cross section of the receiver, the funnel and the piston along the line C—C in Fig. 5.

Figs. 8 and 9 show a cross section and a vertical section respectively of another form of embodiment of the invention. Fig. 10 shows a third form of embodiment thereof.

In Figures 1 to 10, mounted on the frame 16 50 is the vertical receiver 1, which is open at the top and the bottom and is provided with the inlet opening 2 for the tobacco and with the piston 6.

According to Figs. 1 to 7, the inlet channel

or funnel leading to the feeding opening is 55 formed of an inclined front wall or bottom 26 which is pivotally mounted on its lower edge at the receiver by means of the pivots 27, and of the two stationary walls 28 formed on the receiver 1 which bear against each of the side edges of the inclined bottom 26 (see Fig. 3). The said bottom can be swung inwardly so as to wholly cover the feeding opening 2, so as to form a shutter for the opening.

The shutter is held in its inclined open position shown in Fig. 2 by means of a support 50 projecting from the frame 16 and which is provided at the top with a roller 51 bearing against a rib 52 or the like on the outside of the shutter.

The closing and opening of the shutter takes place automatically and in a determined relation to the movement of the other working parts of the machine, as will be seen from the following description of the arrangement 70 and operation of the machine.

Projecting from the side walls of the receiver 1 are pivots 7 and 8 and on each of said pivots there is mounted a double-armed level 9, 10. The level arms 10 are formed 80 with toothed segments at their upper free ends and the said toothed segments mesh with toothed segments on arms 11 secured to a horizontal shaft 21 turnably mounted in bearings 20 on the slide 14. Secured to the lower ends of the downwardly directed arms 9 of the levels 9, 10 is a knife 12. The side walls of the receiver are provided with extensions 13 forming ears for screws or the like by means of which the receiver is secured 90 to the slide 14 which is slidably mounted on the vertical guide rods 15 which are connected to each other by means of the cross piece 17 carrying the piston 6, and are slid- able in vertical guides in the frame 16. 95

The slide 14 is moved up and down by means of rods 18 which engage pivots 19 on the slide and which are driven up and down from a driving shaft 30 by means of the following device: Secured to the shaft 30 are cam disks 100 31 on which bear rollers 32 carried by arms 33 turnably secured to the frame and the swing- ing ends of which are turnably connected to the rods 18 by means of pivots 35.

The rods 15 and also the piston 6 are driven 105 from cam disks 36 on the shaft 30 by means of arms 37 turnably secured to the frame and bearing through the medium of rollers 38

against the cam disks and engaging with their free fork-shaped ends the rods 15 between flanges 34 on the same.

Secured to the shaft 21, through the rotation of which the knife 12 is swung, is an end of an arm 22, the other end of which is turnably connected by means of a pivot 24 to a rod 23 which is reciprocated by the shaft 30 inasmuch as the rod 23 is turnably connected to the one arm of a double-armed lever 39, the other arm of which bears by means of a roller 40 against a cam disk 41 on the shaft 30.

According to Fig. 2 the piston takes an upper position; the shutter 26 is opened and the receiver 1 is filled with a certain number of already compressed portions of filler tobacco supplied through the opening 2. The line 53 designates the upper surface of the compressed tobacco mass. Before the piston is moved downwards a further portion of filler tobacco 54 is fed into the receiver. The outer or free surface of the said portion is indicated by the line 25. The receiver and the piston are now moved downwards, by which the shutter 52 by its abutting against the roller 51 on the support 50 is caused to swing inwards so that, when the parts have reached the position shown in Fig. 5, the shutter has covered the opening and caused the whole portion 54 to enter into the receiver. Before the receiver has reached its lowermost position (Fig. 5), the knife 12, which has formed a bottom for the receiver, swings from the position shown in Fig. 2 to that one shown in Fig. 5, thus uncovering the lower opening of the receiver.

Then the piston continues to move down relatively to the receiver to a predetermined level so as to compress the portion last supplied and the tobacco mass already contained in the receiver against the table 16 to a certain volume. While the piston remains in the said lower position the receiver 1 moves upwards to the position shown in Fig. 6 and also the knife is simultaneously moved upwards but maintains during the said movement its swung-out position so that from the tobacco mass formed by the compressed tobacco portions a certain part corresponding to a desired filler is uncovered. As soon as the position shown in Fig. 6 is reached the knife 12 is swung inwards so as to cut off the said uncovered part of the tobacco mass and to again form a bottom of the receiver. Then the receiver 1 and the piston 6 move together upwards and immediately after they have reached the position shown in Fig. 2 the shutter is swung back to the outer limit position (Fig. 2) under the influence of the spring 64 which has been expanded during the positive closing of the shutter above described.

According to the form of the invention shown in Figs. 8 and 9 the channel is in its entirety shaped as a swingable shutter 60. The closing as well as the opening of the

shutter takes place positively when moving the receiver down and up by means of a link 66 which is pivotally connected to the shutter and to the support 68 by means of the pivots 65 and 67, respectively. In Fig. 8 the shutter is closed and in Fig. 9 the shutter is open. In the form of the invention in Fig. 10 no part of the channel or funnel proper is formed as a shutter, but in this case the shutter is turnably secured to the upper edge of the opening. The device is such that when the shutter is swung (for instance by means of a roller 61 driven by a suitable device and co-operating with a cam 62) from its upper position shown in full lines to its closed position shown by dash and dotted lines, the shutter forces the tobacco contained in the channel into the receiver.

The receiver may have such cross-section shape, that the compressed tobacco will have the cross-sectional form of a cigar filler, as is shown in Figs. 3 and 7 or the form of a so-called cartridge which is of a size to use in a pipe as in Figs. 8 and 9.

Common to all of the described forms of the invention there is arranged a shutter in front of the inlet opening and said shutter forms in its closed position part of the wall of the receiver, and bears tightly against the side surfaces of the piston as it moves past the opening.

The other wall part of the receiver which is situated opposite the inlet opening 2 may also be formed as a shutter which is closed and opened simultaneously with the shutter for the opening 2. By such means a greater space is obtained for the tobacco quantity, which obviously facilitates the feeding of the tobacco and it is also rendered possible feeding the tobacco through two or more openings.

Instead of a spring 64, a weight or any other equivalent means may be used.

What I claim as new and desire to secure by Letters Patent of the United States of America is:—

1. In a machine for compressing and shaping a tobacco mass in correspondence to the tobacco articles to be manufactured, a receiver for the tobacco mass, a part of the wall of said receiver being in the form of a shutter closing a lateral inlet opening of the receiver.

2. In a machine for compressing and shaping a tobacco mass in correspondence to the tobacco articles to be manufactured, the combination of a receiver for the tobacco mass, an inlet opening in the lateral wall of said receiver, a channel in front of said inlet opening, the bottom of said channel being swingable and adapted to close in its inner position the said inlet opening.

3. In a machine for compressing and shaping a tobacco mass in correspondence to the tobacco articles to be manufactured, the com-

- bination of a receiver for the tobacco mass, an inlet opening in the lateral wall of said receiver, a channel in front of said inlet opening, the bottom of said channel being swingable and adapted to close in its inner position the said inlet opening, the said receiver being movable vertically, and means for opening and closing the said bottom automatically at the vertical movement of said receiver.
4. In a machine for compressing and shaping a tobacco mass in correspondence to the tobacco articles to be manufactured, the combination of a receiver for the tobacco mass, an inlet opening in the lateral wall of said receiver, a channel in front of said inlet opening, the bottom of said channel being swingable and adapted to close in its inner position the said inlet opening, the said receiver being movable vertically, a frame, a support on said frame, said support being adapted to hold the bottom in an inclined open position when the receiver is in its lower position, and to close the said bottom when the receiver moves to its upper position.
5. In a machine for compressing and shaping a tobacco mass in correspondence to the tobacco articles to be manufactured, the combination of a receiver for the tobacco mass, an inlet opening in the lateral wall of said receiver, a channel in front of said inlet opening, the bottom of said channel being swingable and adapted to close in its inner position the said inlet opening, the said receiver being movable vertically, a frame, a support on said frame, said support being adapted to hold the bottom in an inclined open position when the receiver is in its lower position, and to close the said bottom when the receiver moves to its upper position, and a spring tending to move the bottom to its open position.
6. In a machine for compressing and shaping a tobacco mass in correspondence to the tobacco articles to be manufactured, a receiver for the tobacco mass, a part of the wall of said receiver being in the form of a shutter closing a lateral inlet opening of the receiver, the cross section of said receiver having the same shape as the tobacco article to be manufactured, a vertically movable piston projecting into the upper end of said receiver and adapted to compress the tobacco mass in the receiver.
7. In a machine for compressing and shaping a quantity of tobacco mass the combination of a vertical casing for receiving the mass, a piston within said casing, said piston and casing being movable vertically and adapted to press together the tobacco mass in the casing by such vertical movement, the casing being provided with a lateral opening, serving as inlet for the tobacco mass, and a shutter for said inlet opening.
8. In a machine for compressing and shaping a quantity of tobacco mass the combination of a vertical casing for receiving the mass, a piston within said casing, said piston and casing being movable vertically and adapted to press together the tobacco mass in the casing by such vertical movement, the casing being provided with a lateral opening, serving as inlet for the tobacco mass, a channel in front of said inlet opening, the bottom of said channel being swingable to and from said opening and adapted to close in its inner position the said inlet opening.
9. In a machine for compressing and shaping a quantity of tobacco mass the combination of a vertical casing for receiving the mass, a piston within said casing, said piston and casing being movable vertically and adapted to press together the tobacco mass in the casing by such vertical movement, the casing being provided with a lateral opening, serving as inlet for the tobacco mass, a supply channel for said inlet opening, the bottom of said channel being pivoted at the lower edge of said inlet opening and forming a shutter for the latter.
10. In a device for manufacturing tobacco fillers for cigars the combination of a casing for receiving a quantity of tobacco mass, the cross section of the inside of said casing corresponding to the longitudinal section of the desired filler, a piston located within and guided by said casing, the piston and casing being movable in relation to each other and adapted to press together the tobacco mass in the casing by such relative movement, an opening in the piston guiding wall of said casing, said opening serving as inlet for the tobacco mass and a shutter for said inlet opening.
11. In a device for manufacturing tobacco fillers for cigars the combination of a vertical casing for receiving a quantity of tobacco mass, the cross section of the inside of said casing corresponding to the longitudinal section of the desired filler, a piston located within and guided by said casing, the piston and casing being movable in relation to each other vertically and adapted to press together the tobacco mass in the casing by such relative movement, an opening in the lateral wall of said casing, said opening serving as inlet for the tobacco mass, a tobacco supply channel for said inlet opening, the bottom of which is adapted to serve as a door for said opening.

In testimony whereof I affix my signature.
ERNST RUBEN DAHLSTROM.
